(57) **CLAIM**

The ornamental design for ceiling light for an aircraft, as
shown and described.

DESCRIPTION

FIG. 1 is a bottom, front, right side perspective view of a
ceiling light for an aircraft showing my new design

FIG. 2 is a bottom plan view thereof;

FIG. 3 is a top plan view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a bottom, front, right side perspective view of a
second embodiment of a ceiling light for an aircraft;

FIG. 9 is a bottom plan view thereof;

FIG. 10 is a top plan view thereof;

FIG. 11 is a front elevation view thereof;

FIG. 12 is a rear elevation view thereof;

FIG. 13 is a right side elevation view thereof; and,

FIG. 14 is a left side elevation view thereof.

The dashed broken lines in the drawings illustrate the portions
of the design that form no part of the claim. The dot-dash
broken line(s) define the bounds of the claim and form no part
thereof.
